United States Patent Office.

ROYAL L. WOODBURY, OF LEXINGTON, MASSACHUSETTS.

Letters Patent No. 106,016, dated August 2, 1870.

IMPROVED LAP-BOARD FOR DRESS-MAKERS.

The Schedule referred to in these Letters Patent and making part of the same

I, ROYAL L. WOODBURY, of Lexington, in the county of Middlesex and State of Massachusetts, have invented certain Improvements in Lap-Boards for the use of Dress-Makers and Seamstresses, of which the following is a specification.

Nature and Objects of the Invention.

My invention consists of devices more fully hereinafter described.

Description of the Accompanying Drawing.

Figure 1 is a view of the upper surface of the lap-board, showing the position of the measuring-rule, pin-cushions, and emery-cushions.

Figure 2 is an end view of the board, showing the edge of a thin strip of wood, let in for the purpose of strengthening the board.

Figure 3 is an enlarged view of a portion of the measuring-rule, as marked upon the board.

Figure 4 shows the construction of the board, when made up of strips of wood, of different colors, glued together.

General Description.

The lap-board may be of any desired size. I construct it three feet long, twenty-one inches wide in the widest part, and not over five-eighths of an inch thick.

About midway between the outer and inner edges, and lengthwise of the board, I make, upon the upper surface of the board, or upon both surfaces, with stamping-chisel and dies, a three-foot measuring rule, *a b*, fig. 1, which is also marked off to show one-eighth yard, one-fourth yard, three-eighths yard, &c., as may be seen in fig. 3.

At several convenient points, *c c c*, &c., fig. 1, on the flat surface of the board, between its outer edge and the measuring-rule, I bore smooth three-eighth inch bit-holes perpendicularly quite through the board, and afterward draw into said holes, which are first moistened with glue, folded strips of fine, firm woolen

felt. These plugs of felt are afterward cut off flush with the surfaces of the board.

Into the inner edge of the board, at the right and left hand alike, I bore, perpendicularly, a bit-hole, an inch deep or more, and as large as the thickness of the board will permit. While this hole is moist with glue, an emery-cushion, made to fit it closely, and so long as just to protrude and be easily seen, *d d*, fig. 1, is firmly pressed into it.

The board so constructed may, for all purposes not requiring the use of the measuring-rule, be used equally well with either surface uppermost.

After the board is cut to near its finished dimensions, I cut a deep groove in each end of it, say, two inches deep, and into this, moistened with glue, press a closely fitting thin strip of hard wood, similarly moistened, with the grain crossing the grain of the board. The whole is firmly pressed together till quite dry. This will tend to prevent the splitting or springing of the board.

For security against warping I sometimes construct the board, out of which the lap-board is cut, of narrow strips of seasoned wood, planed very accurately on both the upper and under surfaces, and on the edges, glued together, edge to edge, and dried in that position, under immense pressure.

An artificial board or plank of this construction is very firm, and will warp less than one cut in a single piece from a large timber. I apply this well-known principle to the lap-board.

I claim as my invention—

The combination of the measuring-rule, pin-cushions, and emery cushions, with the lap-board, constructed in the manner shown, viz., by letting strengthening strips into grooves at the ends, all substantially as and for the purposes hereinbefore set forth.

ROYAL L. WOODBURY.
